UNITED STATES PATENT OFFICE

166,303

SPOT WELDER

Charles Eisler, South Orange, N. J.

Application August 15, 1951, Serial No. 16,290

Term of patent 7 years

(Cl. D26—5)

To all whom it may concern:

Be it known that I, Charles Eisler, a citizen of the United States, residing in South Orange, Essex County, New Jersey, have invented a new, original and ornamental Design for a Spot Welder, of which the following is a specification; reference being had to the accompanying drawing, forming a part hereof:

Fig. 1 is a perspective view of a spot welder, embodying my new design, and

Fig. 2 is a similar perspective view taken from the other side of the spot welder.

I claim:

The ornamental design for a spot welder, as shown.

CHARLES EISLER.
